(57) **CLAIM**

The ornamental design for a set of model vehicle pivoting axle carriers as shown and described.

DESCRIPTION

FIG. 1 is an upper, right, front perspective view of a set of model vehicle pivoting axle carriers showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is an upper plan view thereof;

FIG. 7 is a lower plan view thereof;

FIG. 8 is an upper, left, rear perspective view thereof;

FIG. 9 is a lower, left, rear perspective view thereof;

FIG. 10 is a lower, left, front perspective view thereof; and,

FIG. 11 is a lower, right, rear perspective view of a set of model vehicle pivoting axle carriers.

In the drawings, the broken lines illustrate portions of the set of model vehicle pivoting axle carriers that form no part of the claimed design.
